SEAT

Samuel J. Meiselman, Lynbrook, N. Y., assignor to
Edna Meiselman, Lynbrook, N. Y.

Application January 26, 1944, Serial No. 519,727

4 Claims. (Cl. 155—131)

This invention relates to seats, and more particularly to toilet seats for the use of small children; seats for swings, for chairs and for many other uses.

An object of the invention is to provide a seat of the character mentioned, which is provided with a bottom, a back, sides or arms, and a guard rail, with these elements held in assembled relationship without the use of nails, screws or other metallic fasteners, whereby the seat can be assembled by its purchaser or speedily disassembled when desired, for ease in shipment or carriage.

Another object of the invention is to provide a seat of the kind described wherein the several parts are interfitting and held together by means placed in position without the use of tools, whereby assembly costs are dispensed with, and a convenient, inexpensive and sturdy structure is provided.

In the accompanying drawing, wherein an illustrative embodiment of the invention is disclosed; Fig. 1 is a face view, with a part in section, of the bottom or base of the seat; Fig. 2 is a face view of one of the arms or side members; Fig. 3 is a face view of the back member; Fig. 4 is a view of the slotted guard rail; Fig. 5 is a plan view of the assembled seat; Fig. 6 is a side view of the assembled seat, with a part shown in section to disclose construction; Fig. 7 is a front view of the assembled seat; and Fig. 8 is a sectional view on the line 8—8 of Fig. 5, looking in the direction of the arrows.

The seat shown in the drawing is of a design intended for use as a small child's toilet seat adapted for placement upon the conventional seat member that is hingedly attached to a toilet bowl. It will be understood that with relatively slight modification, the seat shown may be adapted for other purposes, such as for example, the seat of a child's swing, the seat of a chair or the like. Therefore, when herein referring to a seat, I wish to comprehend by that term, any use to which the device may be put, as above set forth.

In the form shown, the seat is provided with a base or bottom member 1, herein referred to as the "bottom," and which is preferably made of wood, or possibly of some sheet material of suitable strength and thickness. Said bottom 1 is provided with the central aperture 2, if the seat is to be used as a toilet seat. In its front edge 3, the bottom 1 is provided with a pair of spaced notches 4, each of which is situated adjacent to one of the side edges 5 of the bottom. In its rear edge 6, the bottom 1 is provided with a pair

of spaced apart recesses 7 intended for the reception of fastening pins 8 which are also extended through the lower part of the back 9 of the seat, as hereafter described.

The seat is provided with a pair of side members or arms 10, each of which is in the form shown in Fig. 2, and of substantially triangular or other suitable shape. At its widest end, constituting the forward end of the arm, each of the arms is provided with an integral, downwardly dependent hook portion 11, the shape of which forms the notch 12. In placing the arms 10 in position so that the same rise from the bottom 1 in the manner shown in the drawing, the hooked elements 11 are inserted in the notches 4 of the bottom 1 so that the nose portion 13 of each of these hooked elements engages beneath the bottom, as shown in Fig. 6, and holds the forward end of its arm in place and prevents it from raising. Before the arms are placed in the position mentioned, they are located in properly spaced relation by the insertion of the guard rail 14 shown in Fig. 4. Said guard rail 14 consists of a rod, which may be made of wood if desired, split inwardly from its opposite ends as indicated at 15. Near each end, the rod 14 has parts of reduced diameter, as indicated at 16; these portions of reduced diameter fitting through the holes 17 provided in the side members 10 at the upper portion of said arms near their forward ends. At each end of the rod 14 is a slightly tapered head 18, which can be forced through the hole 17, due to the split 15, to enable the reduced part 16 of the rod to enter the hole. When the two side members 10 are disposed in the reduced portions of the rod 14, they are located in properly spaced relation to enable the hook members 11 to be inserted in the notches 4 in the front edge 3 of the bottom 1 of the seat. The rod 14 not only serves to hold the arms or side members 10 in properly spaced relation, but it acts as a guard rail at the front of the seat to prevent a small child from sliding or falling from the seat.

The back member 9 of the seat is provided in its lower edge with a pair of spaced notches 19, each of which fits into engagement with a complementary notch 20 formed in each of the two arms or side members 10, said notches 20 being located in the upper edge of each arm near its rear end. The interengagement of the notches 19 and 20 holds the rear ends of the side members 10 in properly spaced relationship and holds the back in an upright position. It will be observed that when the back is engaged with the

side members in the manner described, the lower portion of the back member will extend over the rear edge 6 of the bottom 1. When in this position, spaced holes 21 extending through the back member 9, will be in alignment with the recesses 7 in the rear edge 6 of the bottom 1. Fastening pins 8 are now inserted through the aligned holes 21 and recesses 7 and these pins serve to hold the back against raising movement. Since the notches 20 in the back member 9 are engaged over the tops of the side members, as shown in Fig. 8, the rear portions of the side members cannot rise, and since the front portions of the side members 10 are held down by engagement of the hooked elements 11 beneath the bottom 1, it will be apparent that the various parts of the device, and particularly the three wall elements 10, 10 and 9, are securely held together in the relationship described, and such locked relationship of the parts is maintained as long as the pins 8 are in place. The pins 8 may be of wood if desired and may be a tight fit in the holes 21 and recesses 7 so that they will frictionally hold their positions, until manually removed. If a permanent assembly of the seat is desired, the pins 8 may be glued in place.

It is to be noted that the seat may be assembled readily by simple interfit of the several parts accompanied by the manual insertion of the two small pins 8, and a strong structure results, yet one which may be dismantled almost instantly by removal of the pins 8 and the separation of the notched parts, to allow the seat to be packed flat for convenience in carrying or shipping. Since no tools are required for the assembly of the seat, no assembly cost is involved and as a result the device may be inexpensively manufactured.

While I have herein illustrated the seat for use as a toilet seat, it will be obvious that it may be embodied in various other structures and designs, all comprehended within the invention and within the scope of the claims appended hereto.

What I claim is:

1. A seat of the character described comprising, a bottom, a pair of side members, a back, a guard rail, the bottom being notched at its forward edge and recessed in its rear edge, the side members having hooked elements engaging in the notches in the forward edge of the bottom member, the back being notched to interfit with the side members adjacent to the rear ends of said side members, the back having apertures in registration with the recesses in the rear edge of the bottom, pins removably fitted through said apertures and extending into the recesses, and the guard rail extending between and removably connecting the side members at the front end of the seat.

2. A seat of the character described comprising, a seat bottom, spaced side members rising from the top face of the bottom, the forward edge

of the bottom having spaced notches, the lower edge of the side members having hooked elements entering said notches, the top edge of the side members being notched near the rear ends of said side members, a back member having notches in its lower edge near its opposite ends, the notches in said back member engaging those in the side members, and fastening pins extending through the back member near its lower edge and entering into the rear edge of the bottom, said pins preventing raising movement of the back member, and the notched engagement between the back and side members holding the rear portions of the side members against raising movement relative to the bottom.

3. A seat of the character described comprising, a seat bottom, spaced side members rising from the top face of the bottom, the forward edge of the bottom having spaced notches, the lower edge of the side members having hooked elements entering said notches, the top edges of the side members being notched near the rear ends of said side members, a back member having notches in its lower edge near its opposite ends, the notches in said back member engaging those in the side members, fastening pins extending through the back member near its lower edge and entering into the rear edge of the bottom, said pins preventing raising movement of the back member, and the notched engagement between the back member and side members holding the rear portions of the side members against raising movement relative to the bottom, and a guard rail connecting the side members at the forward ends of said members, said guard rail consisting of a split member having means by which it maintains the side members in spaced relation.

4. A seat of the character described comprising, a bottom, a pair of triangularly shaped side members, a back, a front guard rail, the bottom having spaced notches in its forward edge and having spaced recesses in its rear edge, each of the side members having a downwardly dependent hook member at its forward edge fitting in the notches in the bottom, said hook members engaging beneath the bottom and preventing raising movement of the front parts of the side members, the side members having notches in their upper edges adjacent to their rear ends, the back being notched in its lower edge to engage with the notches in the upper edges of the side members, the back having spaced holes extending through it near its lower end, said holes aligning with the recesses in the rear edge of the bottom, pins removably extending through said holes and entering the recesses in the bottom, the guard rail extending between and connecting the side members at the front upper ends of said members, said guard rail having split end portions, the side members having holes in which said split portions of the guard rail are received.

SAM. J. MEISELMAN.
